UNITED STATES PATENT OFFICE.

JOHN C. WORKING, OF BAKERSFIELD, CALIFORNIA, ASSIGNOR TO WORKING METAL DOOR COMPANY, OF LOS ANGELES, CALIFORNIA, A CORPORATION OF CALIFORNIA.

COLLAPSIBLE DOOR.

Application filed October 31, 1921. Serial No. 511,620.

To all whom it may concern:

Be it known that I, JOHN C. WORKING, a citizen of the United States, residing at Bakersfield, in the county of Kern and State of California, have invented certain new and useful Improvements in Collapsible Doors, of which the following is a specification, reference being had to the accompanying drawings.

10 Broadly speaking, as the prior art will show, collapsible doors have heretofore been produced, but there are none that are practical, efficient, and at the same time simple enough to warrant their application to garages, warehouses and the like, namely to close door or window openings, or to act as partitions.

Therefore, it is the purpose of the present invention to provide a sheet metal multiple 20 section collapsible door, adapted to be so mounted in suitable and proper guides at the top and bottom of the door opening, in order to entirely close the opening, without leaving an opening at the top.

25 Doors of this general character which have heretofore been produced, have their sections operated by lazytong bars, but it has been found that the connections between these bars and the sections are not of such 30 character as to warrant a practical construction, sufficient to insure a fire and storm proof closure.

Therefore another purpose is to provide a door of this character, wherein the sections 35 are hingedly connected throughout their entire adjacent edges, to insure a practical fire and storm proof closure, the lazytong bars including an improved pivotal connection between the pivotally united centers of 40 the bars and alternate hinged edges of the sections, so that when the lazytong bars are operated, the sections of the door may become extended or collapsed.

Also heretofore lazytong bars have been 45 connected to door sections, which consist of a plurality of strips, with inside and outside pliable material or fabric, enclosing the lazytong bars, which are connected to the strips, the pliable or flexible material, 50 such as fabric becomes folded or stretched as the door opens.

The present invention aims to obviate such pliable or flexible material, and in lieu thereof to employ a multiple of relatively 55 narrow door strips, hinged together through-

out their entire adjacent edges, and so mounted, whereby the strips, when collapsed, extend inwardly of the door opening, thereby precluding the weather, in case the door is only partly opened or partly collapsed. It is true that this principle is involved in collapsible doors heretofore provided, but this principle is only used, wherein the sections are actually in the form of individual doors, but which are not actuated by lazytong bars as in the present invention.

Therefore, for the above reasons, a still further purpose is to provide a practical, efficient and very simply constructed collapsible fire and storm proof door, which may be easily and quickly opened and closed, and particularly adapted for garages and large warehouses.

A still further purpose is the provision of 75 a door of this character, wherein the upper and lower ends of the hinge pins which connect the entire longitudinal edges of the door sections have anti-frictional rollers, engaging guides at the top and bottom of the door opening, in order to insure an easier and quicker operation of the door.

While the design and construction at present illustrated and set forth are deemed preferable, it is obvious that as a result of a reduction of the invention to a more practical form for commercial purposes, the invention may be susceptible of changes, and the right to these changes is claimed, provided they are comprehended within the 90 scope of what is claimed.

The invention comprises further features and combination of parts, as will be hereinafter set forth, shown in the drawings and claimed.

In the drawings:—
Figure 1 is a view in elevation of a portion of the wall of a garage or warehouse showing the improved collapsible and extensible door as applied;

Figure 2 is a horizontal sectional view on line 2—2 of Figure 1, longitudinally through the upper guide, showing the rollers on the upper ends of the hinge pins which connect the longitudinal edges of the sections;

Figure 3 is a horizontal sectional view on line 3—3 of Figure 1 at a point where the lazytong bars are connected to the door sections, thereby showing the construction of said parts;

Figure 4 is a vertical sectional view on line 4—4 of Figure 1, showing the connections between the lazytong bars;

Figure 5 is a sectional view on line 5—5 of Figure 1;

Figure 6 is an enlarged detail view of the connections between the centers of the lazytong bars and the hinge edges of the sections.

Referring to the drawings, 1 designates 10 the door opening, at the top and bottom of which guides 2 and 3 are arranged.

Mounted in the door opening 1 is a pair of extensible and collapsible doors 4. While there are two doors disclosed, it is obvious 15 that only one may be used. Each door comprises a plurality of sheet metal sections 5 relatively narrow and hingedly united along their vertical edges as shown at 6. In fact the hinges extend the entire length of the 20 sections, in the form of piano hinges, and the upper and lower ends of the hinge pins have anti-frictional rollers 7 and 8, engaging in the guides 2 and 3. In fact the extreme lower ends of the hinge pins have rollers 9, 25 which ride upon the bottoms of the lower guide, thereby supporting the doors in their opening and closing movements. The remote end sections of the doors are hingedly connected by piano hinges 10 to the angle 30 iron jambs of the door opening; the flanges 11 of the jambs 12 are broad enough to overlie the sections of the doors when collapsed, in order to protect them from the vehicles when passing in and out of the garage. The 35 adjacent end sections of both doors are hingedly united by piano hinges 13 to angle strips 14, the flanges 15 of which sufficiently overlie the sections of the door, when collapsed, and cooperate with the flanges of 40 the jambs, so as to completely hide the door sections when collapsed, and thereby further protect the door sections. The adjacent angle strips of the doors may be provided with a conventional form of lock, 45 whereby the two doors may be secured together when extended for closing the door opening.

In order that the door sections may collapse, a plurality of lazytong bars 16 connect between the adjacent angle strips of the doors, and the remote jamb angle strips, and where the lazytong bars are connected to these angle strips, the pivotal connections are designated by the numerals 18 and 19.

50 The lazytong bars have their remote ends pivotally united as at 20, while their centers are pivotally connected as at 21. The pivot pins 21 have certain of their ends swaged or headed, to prevent movement of the pivot pins in one direction, while their other ends terminate in rings 22, through which the hinge pins of alternate hinges of the door sections pass, thereby pivotally connecting the door sections to the lazytong bars. The 55 pivot pins connecting the lazytong bars are

mounted in suitable bushings, so as to insure ease and quick movements of the lazytong bars, when opening and closing the doors. While the drawing shows the doors operated to open and collapse in horizontal directions, it is obvious that the doors may be disposed so as to open and collapse in vertical directions.

The invention having been set forth, what is claimed is:—

1. In an extensible and collapsible door, the combination with a structure having a door opening, and guides at the top and bottom of the opening, of an extensible and collapsible door comprising a plurality of door sections mounted in the opening, means hingedly uniting the longitudinal edges of the sections throughout their entire length, the upper and lower ends of the hinge pins of every other hinge means having mountings to engage said guides, whereby the sections of the door may extend inwardly of the door opening when the sections are collapsed.

2. In an extensible and collapsible door, the combination with a structure having a door opening, and guides at the top and bottom of the opening, of an extensible and collapsible door comprising a plurality of door sections mounted in the opening, and connections including hinge pins uniting the longitudinal adjacent edges of the sections throughout their entire length, the upper and lower ends of the hinge pins of every other hinge connection having mountings to engage said guides, whereby the sections of the door may extend inwardly of the door opening when the sections are collapsed, and means operatively connecting the sections, whereby they may be extended or collapsed in unison during the opening and closing movement of the door.

3. In an extensible and collapsible door, the combination with a structure having a door opening and guides at the top and bottom of the opening, of an extensible and collapsible door comprising a plurality of door sections mounted in the opening, hinge connections including hinge pins and uniting the longitudinal adjacent edges of the sections throughout their entire length, the upper and lower ends of the hinge pins of every other hinge connection having mountings to engage said guides, whereby the sections of the door may extend inwardly of the door opening when the sections are collapsed, and a plurality of lazytong bars connecting the end sections of the door and having their pivoted centers operatively connected to every other hinge joint of the sections, whereby the sections of the door may be extended and collapsed in unison when the door opens and closes.

4. In an extensible and collapsible door, the combination with a structure having a

door opening and guides at the top and bottom of the opening, of an extensible and collapsible door comprising a plurality of door sections mounted in the opening, hinge connections including hinge pins and uniting the longitudinal adjacent edges of the sections throughout their entire length, the upper and lower ends of the hinge pins of every other hinge connection having mountings to engage said guides, whereby the sections of the door may extend inwardly of the door opening when the sections are collapsed, a plurality of lazytong bars connecting the end sections of the door, and pivot pins connecting the centers of the lazytong bars, said pivot pins having eyes through which the hinge pins of every other hinge connection between the sections engage, whereby the sections may collapse in unison.

5. In an extensible and collapsible door, a structure having a door opening, guides at the top and bottom of said opening, an extensible and collapsible door mounted in the opening, said door comprising a plurality of sections, hinge connections uniting the sections along their entire adjacent edges and including hinge pins, means connected to every other hinge connection between the sections at the top and bottom of the door and engaging the guides so as to hold the door mounted in the opening, a series of lazytong bars connecting the end sections of the door, pivot pins connecting the centers 25 of said lazytong bars, said pivot pins having eyes at certain of their ends to receive the hinge pins between every other connection between the door sections, whereby the

sections may operate in unison when the door is opened and closed.

6. In an extensible and collapsible door, a structure having a closure opening, an extensible and collapsible door mounted in guides thereof, said door comprising a plurality of sections, hinge connections including hinge pins and uniting said sections along their entire adjacent edges, lazytong bars connecting the end sections of the door, pins pivotally connecting the centers of the lazytong bars, said pins having certain of their ends provided with means operatively receiving the hinge pins of every other hinge connection between the door sections, whereby the door sections may extend and collapse in unison and extend inwardly of the door opening when collapsed.

7. The combination with a structure having a door opening, and guides at the top and bottom of the opening, of an extensible and collapsible, door mounted in said opening and provided with means engaging said guides, said door comprising a plurality of sections, hinge connections uniting the door sections along their entire adjacent edges, said hinge connections including hinge pins, a series of lazytong bars connecting the end sections of the door, pivot pins connecting the centers of said lazytong bars and provided with circular eyes at their inner ends, the hinge pins of said hinge connections between the sections passing vertically through said eyes, whereby the door sections may move inwardly when collapsed.

In testimony whereof I hereunto affix my signature.

JOHN C. WORKING.
